UNITED STATES PATENT OFFICE.

HENRY T. PAISTE, OF PHILADELPHIA, PENNSYLVANIA, ASSIGNOR TO H. T. PAISTE COMPANY, OF PHILADELPHIA, PENNSYLVANIA, A CORPORATION OF PENNSYLVANIA.

FUSE PLUG.

Application filed October 27, 1922. Serial No. 597,328.

To all whom it may concern:

Be it known that I, HENRY T. PAISTE, a citizen of the United States, residing in Philadelphia, Pennsylvania, have invented 5 a Fuse Plug, of which the following is a specification.

One object of this invention is to provide a fuse plug of the type including a renewable fuse-carrying capsule, which shall be 10 simple and substantial in construction and which shall insure good electrical contact between the fuse on the capsule and the terminal shell on the plug body.

Another object of my invention is to provide 15 a fuse plug of the above type including a body of insulating material of novel form particularly adapting it to be conveniently held and turned when it is desired to screw the plug into or out of a receptacle.

I also desire to provide a capsule carrying a relatively fusible link and especially designed for use in a fuse plug of the above noted type, the invention including a novel 25 construction for holding in place the otherwise free end of the fusible element so that this will not spring outwardly from the capsule and become bent or broken.

It is further desired to provide a fuse 30 plug body with novel means for removably holding therein a capsule carrying a fuse or fusible link.

In the drawings herewith:

Figs. 1 and 2 are respectively a side elevation and a plan of the fuse plug constituting my invention;

Figs. 3 and 4 are respectively a side elevation and an inverted plan of the fuse plug capsule;

Figs. 5 and 6 are respectively a plan and an inverted plan of the fuse plug body with the capsule removed;

Fig. 7 is a longitudinal vertical section on the line 7—7, Fig. 5; and

Fig. 8 is a longitudinal vertical section of the fuse capsule taken through the fusible link.

In the above drawings, 1 represents an elongated, substantially cylindrical casing 50 of insulating material such as porcelain, having one end closed and formed with a cavity 3, which while for the most part of circular cross section, has a portion 4 ad-

jaacent its open end of polygonal section,— in the present case hexagonal. The external 55 cylindrical surface of the casing 1 has longitudinal grooves 5 extending from one end to the other, each communicating with radially extending grooves 6 formed in the open end of the casing, which latter grooves 60 open into the cavity of said casing.

Mounted on the open end of the casing 1 is a threaded sheet metal shell 7 formed to screw into a standard lamp socket or receptacle and having one edge notched or forced 65 into certain of the longitudinal grooves 5, as indicated at 8. Those grooves into which said shell is extended are formed with shoulders 9 against which the portions 8 of the shell abut to prevent it being drawn 70 off the end of the casing. Said shell 7 is inwardly flanged as indicated at 10 so as to extend over the otherwise open end of the casing 1 and is thereafter cut to form a series of angular tongues 11 which are 75 bent into the portion 4 of the cavity to lie immediately adjacent the flat walls thereof. These tongues however do not lie immediately in contact or parallel with said walls but extend toward each other 80 so as to form more or less yielding contact members for engagement with a fusible link on the fuse capsule. The radial passages 6 in the end of the casing permit of the escape of gases from the cavity 3 into the longitudinal groove 5, since the tongues 11 are 85 spaced away from and make a more or less loose fit with the walls of the casing.

The fuse capsule consists of a more or less tapering body including a portion 12 90 of circular section and a portion 13 of hexagonal section formed with an integral head or flange 14. This structure is made of porcelain and the body 12—13 is formed with a cavity 15 opening into its unflanged 95 end. A strip of relatively fusible metal 16 has one end in electrical engagement with a metal terminal 17 in the form of a piece of sheet material having a branched body extending into the flange 14 and including 100 two oppositely projecting semi-circular portions lying against the otherwise flat outer face of said flange adjacent the center thereof.

One end of the fusible strip 16 extends 105 between the branches of this terminal mem-

ber and is formed in two tongues bent at right angles in opposite directions so as to lie parallel and in engagement with the semi-circular portions of said terminal 17. 5 From the latter the link extends centrally through the flange into the cavity 15 of the fuse body, then outwardly through a notch in the edge of the open end thereof and back in engagement with the external 10 surface of said body to the under side of the flange. Here it is offset as indicated at 18, being bent into a recess of said flange so as to be effectually held in place and then extended radially out over the under 15 surface of the flange.

The body 12-13 is of such dimensions as to be capable of entering the cavity 4-3 of the casing 1, the flat sides of the portion 13 being formed to cooperate with the spring 20 tongues 11, which frictionally engage it to removably hold the capsule in the casing after it has been inserted. When in this position, the portion of the fusible link extending over the external surface of the 25 body 12-13 is electrically engaged with one of the tongues 11 and when the capsule is forcibly pressed into engagement with the turned in portion 10 of the shell 7, the latter, engages the outwardly projecting 30 part 16^a of the link.

The casing with its parts and the capsule therefor constitute a fuse plug which may be screwed into a receptacle of suitable construction, whereupon the oppositely projecting ends 16^b of the fusible link are engaged with one terminal of said receptacle, from which the circuit is completed through 35 the fusible link to one of the spring tongues 11, thence to the threaded shell 7 and to the 40 second terminal of the receptacle.

In the event of an abnormally heavy current flow through the fusible link 16, this is fused in the ordinary manner and, as above noted, any gases formed or resulting 45 from this fusing, pass out between the tongues 11 and the walls of the cavity 3, thence into the passages 6 and to the grooves 5, through which they are led so as to escape into the air.

50 By reason of the polygonal cross section of the portion 4 of the casing 1 and of the opening in the shell 7, the similarly formed portion 13 of the capsule body is prevented from rotating, after being inserted. As a

consequence when the plug is rotated by a 55 turning force applied to its casing 1, the capsule is likewise turned and may be withdrawn with the body from the receptacle in which the plug is used.

I claim:

1. The combination in a fuse plug of a 60 threaded shell inwardly flanged at one end and having spring tongues projecting inwardly from the inner edge of said flanged end; an elongated hollow casing of insulating material having an open end fitting into said threaded shell and having its opposite end integral with its body and closed; there being grooves extending longitudinally in the outer surface of said casing and passages 70 in the edge of the open end thereof communicating with its hollow interior; with a capsule having a portion formed to pass through the opening in the flange of the threaded shell into the casing, and including a link electrically engaging one of the spring 75 tongues, one end of the link terminating at one end of the capsule.

2. The combination in a fuse plug of an 80 elongated substantially cylindrical body of insulating material integrally closed at one end and having longitudinally extending grooves in its external surface; radial passages in the edge of the open end of said casing; a threaded metallic shell fixed on 85 the casing including a flange extending inwardly over the edge of the open end thereof and having spring tongues projecting inwardly into the cavity of the casing; with a fuse capsule comprising a body having a flange at one end formed with a recess in 90 its under side, a fusible link extending from the outer face of said flange through the body, then longitudinally over the external surface thereof into the recess in the under 95 side of the flange.

3. A fuse plug capsule including a body portion having an external flange; a terminal plate on the outer face; and a fuse link, having one end engaging said terminal 100 plate, extending therefrom through the body portion of the capsule to the outside thereof, thence longitudinally over the external surface of the capsule and into a recess in the flange, and then radially outward over the 105 under surface of the flange.

HENRY T. PAISTE.
